MACHINE FOR TWISTING FAN SPIDERS

Peter M. Sampatacos, Torrington, Conn., assignor
to The Torrington Manufacturing Company,
Torrington, Conn., a corporation of Connecticut

Application February 3, 1950, Serial No. 142,328

40 Claims. (Cl. 153—78)

1

The invention relates to a machine primarily adapted and intended for twisting the arms of spiders such as those used for carrying the blades of rotary air impelling fans.

A fan spider of the type for which the machine is adapted to be used initially comprises a flat metallic plate having a centrally apertured main or central portion and having a plurality of integral arms extending outward from the central portion. The central portion serves as a hub or support which is adapted to be mounted on a suitable driving shaft such as the shaft of an electric motor. The blades of the fan are connected with the several arms of the spider by riveting or otherwise, and in order that the blades may be positioned at suitable pitch angles it is necessary for the spider arms to be positioned at corresponding angles with respect to the main or central portion of the spider.

It has been the customary prior practice to first stamp or blank the spider to the required shape, and to then subject it to a pressing operation between suitable dies in order to bend the arms to the required angles. The pressing procedure is expensive and otherwise objectionable.

In the manufacture of fans it is not only necessary to provide numerous sizes of spider but also necessary for each size to provide a wide variety of pitch angles and to provide for rotation in either direction as required. This necessitates the making of a large number of sets of expensive pressing dies each useful for only a single size and for a single angle and for a single direction of rotation. Furthermore, considerable loss of time is required in changing the set-up even when the size remains the same, it being necessary to remove one set of dies from the press and to install and adjust another set of dies whenever the angle of the spider arms is to be changed. A further objection to the pressing procedure is that the arms frequently shift circumferentially and erratically to limited extents during pressing, the result being that two supposedly opposite arms are not exactly opposite. This circumferential shifting of the arms produces an unbalance in the completed fan, which unbalance must be compensated by expensive balancing procedure.

In a machine embodying the invention, the central portion of the spider is firmly clamped and pairs of jaws are provided for gripping the several spider arms. When the jaws of the several pairs are in firm gripping engagement with the arms, the said jaws are turned simultaneously and to the same extents about fixed axes

which are ordinarily radial. The axes of movement of oppositely disposed pairs of jaws are exactly opposite. As the pairs of jaws are turned the spider arms are twisted to the required angles.

5 By a simple adjustment of the machine the extent of twisting can be quickly set at any angle within the capacity of the machine. The direction of twisting can be readily changed. Only one set of tools is required for each spider size.

10 Inasmuch as the opposite spider arms are firmly gripped by the jaws and inasmuch as the axes of turning are exactly opposite, there is no possibility of any circumferential shifting of the arms and they remain exactly opposite after twisting.

The machine includes many novel features of construction and operation which are shown in the drawings and described in this specification.

In the drawings I have shown in detail a preferred embodiment of the invention, but it will be understood that various changes may be made from the construction shown, and that the drawings are not to be construed as defining or limiting the scope of the invention, the claims forming a part of this specification being relied upon for that purpose.

Of the drawings:

Fig. 1 is a plan view of a machine embodying the invention.

30 Fig. 2 is a front view.

Fig. 3 is an enlarged fragmentary vertical sectional view taken along the line 3—3 of Fig. 1.

Fig. 4 is an enlarged bottom view of the spider clamping tool.

35 Fig. 5 is a fragmentary plan view taken in the direction of the arrows 5—5 in Fig. 3.

Fig. 6 is a view somewhat similar to Fig. 3 but showing the parts in different relative positions and showing additional parts in section.

40 Fig. 7 is combined plan and sectional view taken along the line 7—7 of Fig. 6.

Fig. 8 is a fragmentary view taken along the line 8—8 of Fig. 6.

45 Fig. 9 is a view similar to Fig. 8 but showing the parts in different relative positions.

Fig. 10 is an enlarged fragmentary plan view showing a spider and one set of twisting jaws in engagement therewith.

50 Fig. 11 is a schematic view showing the various hydraulic parts of the machine and also showing certain parts of the electrical control system.

Fig. 12 is a diagram of electrical connections.

General organization

The machine comprises a suitable main base

10 upon which all of the mechanically functioning parts are supported, although some of the parts of the control system may be separately supported.

Each spider S to be twisted has a centrally apertured central portion and has a plurality of arms extending outward from the said central portion. Means is provided at or near the center of the base for supporting and clamping the central portion of the spider S, the said spider being clamped in a fixed position. Preferably and as shown, the spider is clamped in a horizontal position, but it will be understood that such terms as "horizontal" and "vertical" are herein used merely for convenience of description and are not intended to limit the scope of the invention. Each successive spider is manually put in place prior to twisting. The base has a large recess at the front to enable the operator to stand in a convenient position for reaching the spider supporting and clamping means.

Pairs of jaws 12, 12 are provided for engaging the respective arms of the spider S, the jaws corresponding in number and in angular spacing to the spider arms. As shown the spider S has four arms which are equally spaced angularly, and there are therefore four pairs of jaws 12, 12 which are equally spaced angularly. When the spider has a different number of arms, the pairs of jaws correspond to the number of arms. When the arms are angularly spaced otherwise than equally, the pairs of jaws are similarly spaced angularly. The pairs of jaws 12, 12 are initially spaced outward from the spider but they are movable inward into spider arm engaging positions, and they are then engaged with the respective arms. After the pairs of jaws have been engaged with the spider arms, the said pairs of jaws are turned simultaneously and to the same extents about horizontal axes to twist the 40 spider arms, the direction and extent of such turning being dependent upon the required direction and extent of twisting of the spider arms.

After twisting, the spider is released by the clamping means and the pairs of jaws 12, 12 are disengaged from the spider arms and are moved horizontally outward and are turned to their initial positions. The spider with the arms thereof twisted is then manually removed by the operator.

The various parts of the machine are preferably operated hydraulically as will be described. Any suitable operating liquid may be used, and this will for convenience be referred to as oil.

For convenience of description, movements of parts to their operative positions and operative movements of the parts will be referred to as "forward" movements. Movements in the opposite directions will be referred to as "return" movements.

Spider supporting and clamping mechanism

Secured to the top of the base 10 at or near the center thereof is a block 14 having a central vertical hole therein. Carried by the block 14 and extending upward therefrom is a spider locator which includes a vertical post 16. The lower end of the post enters and fits the central hole in the block, the post being releasably held in place by a set screw 18. The post 16 has an upper face from which projects a short central centering stud 20. The upper face of the post 16 may be flat or it may be otherwise shaped to conform to any desired bending or forming of the central portion of the spider. The locator preferably has means projecting above the upper face

5 thereof for engaging the spider arms to approximately locate the spider in a predetermined angular position. As shown, the last said means comprises at least two upward projecting lugs 22, 22 secured to the sides of the post 16.

10 The above-described locator is adapted to support and preliminarily locate the spider S, the spider ordinarily being initially flat as shown in Fig. 3. The several parts of the locator are of such size and shape as to be adapted to receive and fit a spider of a particular size and shape. The centering stud 20 enters and closely fits the aperture in the central portion of the spider, and the locating lugs 22, 22 are shaped and positioned so that each of them engages the spider between two of the arms thereof to approximately locate the spider in a predetermined angular position. The lugs 22, 22 while serving to approximately locate the spider are so shaped and positioned as to permit a subsequent minor angular movement of the spider for the final accurate locating thereof. The machine is or may be provided with a plurality of alternately useable locators, each adapted for use with a spider having a particular size and shape. When the machine is to be used for a spider having a different size or shape, a different locator is substituted.

20 An arched bridge 24 is provided having its lower end portions secured to the base 10 adjacent opposite sides thereof. Carried by the bridge 24 at the center thereof and vertically above the post 16 is a vertically movable clamping tool 26 adapted to cooperate with the locator to clamp the spider in a predetermined horizontal position. The tool 26 has a lower face adapted to engage the top of the spider S, and a central recess 28 is provided in the said lower face to provide clearance for the centering stud 20. The lower face of the tool 26 may be flat or it may be otherwise shaped to conform to any desired bending or forming of the central portion of the spider. The upper face of the post 16 and the lower face of the tool 26 are shaped to conform with each other.

30 45 50 55 60 Suitable spider marking projections are preferably provided which engage one or both faces of the central portion of the spider when the spider is clamped between the locator and the clamping tool. The said marking projections may be on the lower face on the tool 26 or on the upper face of the post 16 or on both. Fig. 4 exemplifies marking projections such as may be provided on the lower face of the tool 26. These marking projections are adapted, upon the application of sufficient pressure, for entering the corresponding face or faces of the spider to mark the said face with any required data, such as an arrow indicating the direction of fan rotation, or the manufacturer's name, or patent numbers or the like.

65 70 75 80 85 90 95 For operating the clamping tool 26 there is preferably provided a hydraulic unit which comprises a vertical cylinder 30 and which also comprises a vertically movable piston 32 as shown in Fig. 11. A pipe 34 is provided for supplying oil under pressure to the cylinder 30 above the piston and pipe 36 is provided for supplying oil under pressure to the cylinder 30 below the piston. Connected with the vertically movable piston 32 is a plunger 38 which extends through and fits a hole in the bridge 24. The plunger 38 has a central aperture therein and the clamping tool 26 is releasably held in the said aperture by means of a set screw 40.

As hereinafter explained in detail, the hydraulic unit initially causes the tool 26 to apply only a low pressure to the spider, this pressure being insufficient to mark or bend the spider. Subsequently, after the jaws have been moved into engaging relationship with the spider arms, the hydraulic unit causes the tool 26 to apply a much higher pressure to the spider, this higher pressure being sufficient to cause the marking projections to enter and mark the spider and sufficient to cause the tool 26 and the post 16 to bend or form the spider in the event that the faces of the tool and post are otherwise than flat.

Spider arm gripping jaws and associated mechanisms

As has been stated, pairs of jaws 12, 12 are provided for engaging and gripping the respective arms of the spider S. The jaws and the supporting and actuating mechanisms therefore are identical in construction and a detailed description of one pair of jaws and of one supporting and actuating mechanism will suffice.

Each pair of jaws 12 is carried by the inner end portion of a horizontally extending carrier which is preferably a cylindrical plunger 42, the carrier or plunger 42 being supported for both endwise and rotative movement in a bearing bracket 44 secured to the base 10. The axis of each plunger is preferably radial, but some departure from a radial position is permissible provided that the departure is exactly the same for each two oppositely disposed plungers. The axes of each two oppositely disposed plungers are in any event exactly opposite, and when the axes are radial they are in exact alignment.

For longitudinally moving the plunger 42 there is preferably provided a hydraulic unit which comprises a horizontal cylinder 46 secured to the bearing bracket 44 at one side thereof, and which also comprises a horizontally movable piston 48. Flexible pipes 50 and 52 are provided for supplying oil under pressure to the cylinder 46 at opposite sides of the piston 48. Connected with the piston 48 and extending in the outward direction is a piston rod 54 carrying a yoke 56. The yoke 56 extends into an annular groove 58 formed in a member 60 secured to the plunger 42 at the outer end thereof. It will be seen that when oil is supplied to the cylinder 46 at one side or the other of the piston 48, the piston rod 54 and the yoke 56 serve to move the plunger 42 longitudinally inward or outward. The yoke 56 permits the cylinder to move rotatively as hereinafter described.

In operation, the operator manually places the spider S on the locator with the centering stud 20 entering the aperture in the central portion of the spider and with arms of the spider at opposite sides of the locating lugs 22, 22. The spider is thus at least approximately located for subsequent operations thereon. Thereafter, by means to be described in detail, oil under pressure is supplied to the cylinder 30 above the piston 32, thus forcing the plunger 38 downward so that the tool 26 is engaged with the top of the central portion of the spider. In order that the spider may be subsequently adjusted angularly, only a low pressure is initially applied by the tool 26. This initial pressure is insufficient to cause the before described marking projections to enter and mark the spider.

For accurately limiting the movement of the plunger 42 and of the jaws in the inward direction the yoke 56 is provided with an adjustable

stop screw 62 which is engageable with a suitable fixed abutment at the outer end of the bearing bracket 44. By adjusting the screw 62 the limit of inward movement can be changed in accordance with the size or shape of the spider.

A control device is associated with each carrier or plunger 42. The control device is preferably an electric limit switch 64, this being suitably mounted in fixed position on the bearing bracket 44. The switch 64 is normally open and it has an operating arm carrying a roller 66. A disc 68 is secured to the stop screw 62 in relatively fixed position thereon, the roller 66 of the switch being in position to be engaged by the said disc 68. As the plunger 42 approaches its innermost position, the disc 68 engages the roller 66, as shown in Fig. 7, so as to move the roller 66 toward the left and to thus close the circuit through the switch. The disc 68 is so located on the screw 62 that the circuit is closed substantially simultaneously with the engagement of the end of the screw with the abutment on the bearing bracket. Inasmuch as the disc 68 is carried by the screw 62 and is at a fixed distance from the inner end thereof, the action of the switch is not affected by the adjustment of the screw to change the inner limit of movement of the plunger 42.

The pairs of spider arm engaging jaws have heretofore been referred to collectively as 12, 12. Each pair of jaws comprises opposed lower and upper jaws 70 and 72. The lower jaw 70 is directly carried by the plunger 42 at the inner end portion thereof and in fixed relation thereto. The upper jaw 72 is pivotally connected with the plunger for movement about a transverse horizontal axis. Preferably the jaw 72 is carried by a lever 74 which is pivotally connected with the plunger 42 by means of a transverse horizontal pivot pin 76, the upper portion of the plunger being cut away and centrally grooved to provide space for the said lever. Interposed between the plunger 42 and the lever 74 at the inner side of the pivot pin 76 is a coil spring 78 which tends to move the lever 74 and the jaw 72 upward away from the jaw 70.

The lower jaw 70 has an upper face which approximately registers with and is adapted to engage the bottom face of the corresponding arm of the spider S. A supporting member 80 is provided for the upper jaw 72, this supporting member being connected with the lever 74. The jaw 72 is pivotally connected with the supporting member 80 by means of a transverse horizontal pin 82. The jaw 72 has a lower face which is adapted to engage the top face of the spider arm and it is automatically adjustable about the pivot pin 82 for proper engagement with the said top face. When the plunger 42 is moved forward, the lower and upper faces of the jaws 70 and 72 are respectively positioned underneath and above the spider arm.

Carried by at least one of the carriers 42, and preferably by each of them, is a means for engaging the sides of the corresponding spider arm as the carrier moves inward, this means serving to turn the spider on the stud 20 and to accurately locate the spider in its predetermined angular position. The initial angular locating of the spider by means of the locating lugs 22, 22 is only approximately correct, and the accurate locating thereof is effected by the last said means on one or all of the carriers. As has been stated, the clamping tool 26 initially has only a light pressure against the spider, this pressure being such that the spider is permitted to turn to a slight extent, if required.

Preferably the said means for angularly locating the spider is formed integrally with one of the corresponding jaws. As shown the lower jaw 70 has two opposite upstanding flanges 84, 84 which are best shown in Fig. 10, these flanges having beveled faces 86, 86 at their inner ends. The flanges 84, 84 are spaced apart by a distance equal to the width of the spider arm, and as the jaw moves inward the beveled faces 86, 86 engage the spider arm to accurately locate it angularly, the entire spider being turned, if necessary, with respect to the centering stud 20. The said flanges 84, 84 and beveled faces 86, 86 may be formed on all of the jaws 70, 70, but this is not essential.

The lower jaw 70 is detachably connected with the plunger 42 by means of a removable bolt 88, a clip 90 serving to prevent movement of the jaw about the axis of the bolt. The supporting member 80 for the upper jaw 72 is detachably connected with the lever 74 by means of a removable bolt 92, a clip 94 serving to prevent movement of the supporting member about the axis of the bolt. It will be understood that the jaws 70 and 72 must be of such size and shape as to be adapted to engage the arms of spiders having a particular size and shape. When the set-up of the machine is to be changed for spiders of a different size and shape, one set of jaws is removed and a different set of jaws is substituted.

The upper and lower faces of the jaws 70 and 72 may be flat, but they may be otherwise shaped when the spider arms are initially otherwise than flat or are to be subsequently bent or formed. The spider arms may have been bent or formed so as to be otherwise than flat before the spiders reach the machine. When the spiders have been previously so bent or formed, the faces of the jaws are shaped to conform to the forming of the spider arms so as to properly engage them. In other instances, the spider arms may be flat when they reach the machine, but subsequent bending or forming is required during the operation of the machine. When the spiders are to be bent or formed by the machine, the upper and lower faces are shaped in accordance with the required bending or forming of the arms. By reason of the shapes of the jaw faces, the spider arms are bent or formed when the jaws are engaged with the spider arms as hereinafter described.

When the plunger 42 is in its retracted position, as shown in Fig. 3, the jaws 70 and 72 are separated, as shown, and they remain so separated until the plunger is moved inward to position the jaws at opposite sides of the corresponding spider arms and in gripping relationship therewith. Then the jaws are relatively moved to cause them to grip the corresponding spider arm. With the construction shown the lever 74 is moved about the pivot pin 76 to move the upper jaw 72 downward so that the spider arm is firmly gripped between the said upper jaw 72 and the said lower jaw 70. For moving the lever 74 a plunger 96 is provided which is longitudinally movable within an aperture in the plunger 42. The plunger 96 has a beveled front cam face 98 which engages a roller 100 at the outer end of the lever 74. As the plunger 96 moves relatively inward, the lever 74 is turned in the counterclockwise direction to move the jaw 72 downward.

Connected with the plunger 96 at the outer end thereof is a piston 102 which fits and is movable in a cylindrical hole 104 in the plunger 42, the outer end portion of the plunger 42 thus constituting a cylinder for the piston and the said piston and plunger constituting a hydraulic unit.

5

The end of the hole 104 in the plunger is closed by the before-said member 60. A flexible pipe 106 is provided which communicates with a hole 108 in the member 60, the pipe thus serving to supply oil under pressure to the outer side of the piston 102. A flexible pipe 110 is provided which communicates with holes 112 and 114 in the member 60 and in the plunger 42, the pipe thus serving to supply oil under pressure to the inner side of the piston 102.

By means of the control system to be described oil is supplied through the pipe 106 immediately after the plunger 42 and the jaws 70 and 72 have reached their innermost spider engaging positions. The oil pressure forces the piston inward to engage the cam face 98 with the roller 100 and to thus move the jaw 72 downward to firmly grip the spider arm. When the spider arms are initially flat and when the faces of the jaws are shaped as previously described, the arms are bent or formed by the jaws when the jaws grip the arms.

Spider twisting mechanism

After the several carriers or plungers 42 and the jaws 70 and 72 carried thereby have been simultaneously moved to their innermost positions and after the jaws have been engaged with the respective spider arms, the said plungers are turned simultaneously and to the same extents about their horizontal axes to effect twisting of the said spider arms. The mechanism for effecting the rotative twisting movements of the plungers and jaws will now be described.

A rotatively movable annular member 116 is provided, this being supported on an annular bearing face 118 on the base. The said member 116 is centrally guided by means of a bearing 120 carried by the central block 14. A retaining disc 122 serves to prevent relative upward movement of the said member 116.

The member 116 carries gear segments 124, one such segment being provided for each plunger 42. The lower portion of each plunger 42 is formed with straight longitudinal gear teeth 126 which mesh with the teeth of the corresponding gear segment 124. The teeth of the segment 124 are so formed as to properly mesh with the straight gear teeth 126 on the plunger 42, the plunger thus being free to move longitudinally without disturbing the proper meshing of the gear teeth. It will be seen that when the annular member 116 and the segments 124 thereon are turned about the central vertical axis, the several plungers 42 are correspondingly turned. The jaws 70 and 72 are turned with the plungers, thus twisting the spider arms with which the jaws are engaged. All of the plungers 42 are turned in unison and to the same extents and thus all of the spider arms are twisted in unison and to the same extents.

For rotatively moving the annular member 116 at least one hydraulic unit is provided and preferably there are two such units connected in parallel with each other. The two hydraulic units and the connecting means associated therewith are identical in construction and a detailed description of one of them will suffice.

Each hydraulic unit comprises a cylinder 128 and also comprises a piston 130 in the cylinder. One end of the cylinder is pivotally connected at 132 to a bracket 134 secured to the base. A connecting rod 136 projects from the cylinder at the opposite end, this rod being connected with the piston 130. The connecting rod 136 is pivotally connected at 138 with a bracket 140 connected to and depending from the annular member 116. An

70

75

opening 142 is provided in the base, the bracket 140 extending downward through the said opening. Flexible pipes 144 and 146 are provided for supplying oil under pressure to the cylinder 128 at opposite sides of the piston 130.

Assuming that it is desired to twist the spider arms in the clockwise direction or toward the right, as shown in Fig. 9, oil under pressure is supplied through the pipe 144 to move the piston 130 toward the right. The piston 130 and the piston rod 136 move the annular member 116 and the gear segments in the counterclockwise direction, as indicated by the arrow in Fig. 9, the spider arms being thus twisted in the desired clockwise direction. If it is desired to twist the spider arms in the opposite direction, fluid is supplied through the pipe 146 and the above-described action is reversed. A suitable manually operable reversing valve 148 is provided, as shown in Fig. 11, for enabling the oil to flow through the pipe 144 or the pipe 146 as desired.

For determining and limiting the angle of twisting, an adjustable stop mechanism is provided for limiting the movement of the annular member 116. As shown in Fig. 1, the member 116 carries an outward projecting lug 150, which is movable between two oppositely disposed horizontal stop screws 152 and 154 carried by the base 10, preferably on two of the brackets 44, 44. Assuming that the annular member is to be moved in the counterclockwise direction, the screw 152 is adjusted so that it engages the lug 150 when the said lug is in its initial or neutral position, as shown in Fig. 1. The screw 154 is adjusted to permit the lug 150 to move toward the left to an extent corresponding to the required angle of twisting. By properly adjusting the screw 154 it is possible to obtain any desired angle of twisting within the limits of the machine. If twisting in the opposite direction is desired, the screw 154 is adjusted to engage the lug 150 when in its initial or neutral position, and the screw 152 is adjusted to permit the lug to move to the required extent toward the right.

Upon the completion of twisting, oil is supplied through the pipe 110 and through similar pipes for the other hydraulic units so as to release the jaws from their clamping engagement with the spider arms. Oil is supplied through the pipe 50 and through similar pipes for the other hydraulic units so as to withdraw the plungers 42 and the jaws in the outward direction, and at or about the same time oil is supplied through the pipe 36 to raise the clamping tool 26 out of engagement with the spider. Finally oil is supplied through the pipe 146 or the pipe 144, according to the position of the reversing valve, to restore the member 116 and the parts connected therewith to their initial or neutral positions. When the jaws 70 and 72 have been sufficiently withdrawn from the twisted spider, the said twisted spider is manually removed and an untwisted spider is put in place for the next following operation.

Hydraulic control system

The several before described valve and piston units and also the hydraulic control elements associated therewith are shown schematically in Fig. 11, and the electrical connections are shown diagrammatically in Fig. 12. Many of the hydraulic and electrical elements are not mounted on the base 10 but are mounted on a separate panel. The hydraulic elements shown in Fig. 11 will first be described with some general references to the electrical elements.

A tank 156 is provided for containing a supply of operating liquid which as before stated, is referred to as oil. Associated with the tank 156 is an electric motor 158 which drives a duplex pump unit, the said pump unit comprising a low pressure pump 160 and a high pressure pump 162. Both of the pumps withdraw oil from the tank 156.

The low pressure pump 160 is connected by means of pipes 164 and through check valves 166 and 168 with a main control valve 170. Connected with the pipes 164 between the check valves 166 and 168 are pipes 172 which lead to accumulators 174, 174. As will presently appear, the demands of the system are widely variable and at certain periods the oil requirements exceed the capacity of the pump 160. By providing the accumulators 174, 174, the oil requirements are integrated. Under some conditions excess oil flows from the pump 160 into the accumulators and under other conditions oil from the accumulators flows into the control system.

The high pressure pump 162 is connected by means of pipes 180 and through a check valve 182 with an electrically operated valve 184. By means of a pipe 186 the high pressure pipes 180 are connected to an electrically operated valve 188. An accumulator 190 is connected with the high pressure pipes 180, this being similar in function to the accumulators 174, 174 for the low pressure system.

The valve 170 is operated by solenoids 196 and 198, and it has a neutral position to which it automatically moves when neither solenoid is energized. When the valve is in its neutral position no connections are established through it. For purposes of explanation it may be assumed that the valve 170 is in the position which it normally occupies during operative or forward movements of the several parts of the machine. Movement of the valve to this position is effected or controlled by the solenoid 196. During return movements of the several parts of the machine the valve has another position, movement of the valve to the last said position being effected or controlled by the solenoid 198. While the movements of the valve are controlled by the said solenoids, the valve may be operated by hydraulic connections leading from the high pressure pipes 180. These hydraulic connections are omitted from the drawing for simplicity.

Connected with the main valve 170 is a pipe 200 for supplying low pressure oil to certain of the cylinders and a pipe 202 for the return of the oil from certain of the cylinders. Also connected with the valve 170 is a pipe 204 for the return of oil from the valve to the main tank 156. When the main valve is in its forward position, the pipes 164 are connected with the pipe 200 and the pipe 202 is connected with the return pipe 204.

Connected with the pipe 200 are pipes 206 which connect with the before-mentioned pipe 34 leading to the upper end of the cylinder 30. The before-mentioned pipe 36 connected with the lower end of the cylinder 30 is connected by means of a pipe 208 with the pipe 202 which leads to the valve 170.

A pipe 210 connects the pipes 206 with a pressure controlled valve 212 which valve is connected with the before-mentioned pipe 50 leading to the outer end of the cylinder 46. In addition to the pipe 50 connected with one cylinder 46, there are other similar pipes 50^a, 50^b and 50^c connected with the other similar cylinders. The valve 212

is initially closed, but it is so constructed that it will open when the pressure applied through the pipe 210 rises above a small predetermined amount.

The before-mentioned pipe 52 connected with the inner end of the cylinder 46 is connected with the pipe 202 leading to the valve 170. In addition to the pipe 52 connected with one cylinder 46, there are other similar pipes 52^a, 52^b and 52^c connected with the other similar cylinders.

With the valve 170 in its forward position low pressure oil flows through the pipes 164, 200, 206 and 34 to the upper end of the cylinder 30, thus moving the piston 32 downward so as to press the tool 26 against the top of the spider to initially hold it in place. Inasmuch as the oil pressure is low, only small pressure is applied to the spider and the spider can be adjusted angularly as heretofore described. As the piston 32 moves downward oil flows from the bottom of the cylinder 30 through the pipes 36, 208, 202 and 204 into the tank 156.

When the tool 26 is seated against the spider, downward movement of the piston 32 is stopped and pressure builds up in the cylinder 30 and in the pipes 34, 206 and 210. When this pressure reaches a predetermined amount, the valve 212 is opened thus permitting oil to flow through the pipes 50, 50^a, 50^b and 50^c into the outer ends of the cylinders 46. The pistons 48 are moved inward or toward the left as viewed in Fig. 11, thus moving the corresponding plungers 42 in the inward directions. As the pistons 48 move inward, oil flows from the inner ends of the cylinders 46 through the pipes 52, 52^a, 52^b, 52^c, 202 and 204 into the tank 156.

The valve 184 is connected as before-stated with the high pressure pipes 180. A pipe 214 is also connected with the valve 184, this pipe leading to the main tank 156. In addition, a pipe 216 is connected with the valve 184 which leads to the pipe 206, a check valve 218 being included in the said pipe 216. When the valve 184 is in its initial position, a connection is established between the pipes 216 and 214, but the check valve 218 prevents low pressure oil from the pipes 206 from flowing through these pipes 216 and 214.

When the piston 48 is moved to its extreme inner position, the before-mentioned limit switch 64 is closed. There are four similar limit switches 64 for the four piston and valve units, these limit switches being connected in series and being connected in series with the said electrically operated valve 184. When all four of the limit switches are closed, the valve 184 is electrically actuated to establish a connection between the high pressure pipes 180 and the pipe 216, the connection with the pipe 214 being closed. Thereupon high pressure oil flows through the pipe 216 to the pipe 34, thus applying high pressure to the cylinder 30 above the piston 32. The tool 26 is then pressed downward with greatly increased force so as to more firmly hold the spider and so as to force the projections on the tool 26 into the spider to effect the marking thereof as heretofore described. Furthermore, when the faces of the tool 26 and the post 16 are shaped or formed so as to be otherwise than flat, the central portion of the spider is shaped or formed in conformity with the shapes of the said faces. At the same time, the high pressure oil flows through the pipes 206, 210, 50, 50^a, 50^b and 50^c to the outer ends of the cylinders 46, thus applying increased pressure to the pistons 48 and more positively holding the plungers 42 in their innermost positions.

It will be seen that if, for any reason, any one of the pistons 48 fails to move the corresponding carrier or plunger sufficiently to close the corresponding switch 64, the valve 184 remains in its initial position and the cylinders 30 and 46, 46 are not connected with the high pressure system. This may happen, for instance, when one of the spider arms has been previously bent so that the corresponding jaws 70 and 72 will not clear it. High pressure is applied only when all of the carriers or plungers are moved by the low pressure sufficiently to close all of the switches 64, 64, and therefore no excessive pressure can be applied to force any carrier or plunger against an obstruction encountered by it.

Pipes 220 and 222 connect the pipe 200 with a valve 224 which is initially closed but which is opened upon the application of sufficient pressure thereto. It will be seen that low pressure is initially applied to the valve 224, but this low pressure is insufficient to open the valve. Connected with the valve 224 is a pipe 226 which leads to a pressure reducing valve 228. The before-mentioned pipe 106 connects the valve 228 with the outer end of the cylinder 104. In addition to the pipe 106 connected with the cylinder 104, there are other similar pipes 106^a, 106^b and 106^c connected with the other similar cylinders. The valve 228 is so constructed that it will transmit only a predetermined limited pressure, notwithstanding a much higher pressure in the pipe 226. The pressure transmitted through the valve 228 must be sufficient to cause the jaws to properly grip the spider arms and to bend or form them when this is required.

The before-mentioned pipe 110, connected with the inner end of the cylinder 104 is connected with the pipe 202 leading to the valve 170. In addition to the pipe 110 connected with one cylinder 104, there are other similar pipes 110^a, 110^b and 110^c connected with the other similar cylinders.

When high pressure is established in the pipes 206 as previously described, this pressure is transmitted through the pipes 220 and 222 to the valve 224. The check valve 218 prevents backward flow of the high pressure oil into the low pressure system. The high pressure applied to the valve 224 serves to open it, thus permitting oil to flow through the pipe 226, through the valve 228 and through the pipes 106, 106^a, 106^b and 106^c to the cylinders 104. As stated, the valve 228 prevents pressure above a predetermined amount to be applied to the cylinders 104. The pistons 102 are moved inward or toward the left as viewed in Fig. 11, thus forcing the jaws 72 into engagement with the spider arms, the spider arms being gripped between the jaws 72 and the jaws 70. As the pistons 102 move inward, oil from the inner ends of the cylinders 104 flows through the pipes 110, 110^a, 110^b, 110^c, 202 and 204 into the tank 156.

Oil under pressure is supplied to the cylinders 104 only after the carriers or plungers have been moved inward to their innermost positions so as to close the several switches 64, 64. The jaws 70 and 72 therefore cannot prematurely grip the spider arms.

The valve 188 is connected as before stated with the high pressure pipe 186. A pipe 230 is also connected with the valve 188, this pipe leading to the main tank 156. Pipes 232 are also connected with the valve 188, these pipes leading to

the before-mentioned manually operable reversing valve 148. A flow control valve 234 is connected in the pipes 232. When the valve 188 is in its initial position, a connection is established between the pipes 230 and 232, but there is no pressure to cause oil to flow through the said pipes.

When the valve 148 is in one position, the pipes 232 are connected with the pipe 144 which is connected with one end of the cylinder 128. In addition to the pipe 144 connected with the said end of the cylinder 128, there is another similar pipe 144^a connected with the other similar cylinder. When the valve 148 is in its other position, the pipes 232 are connected with the pipe 146 connected with the opposite end of the cylinder 128. In addition to the pipe 146 connected with the last said end of the cylinder 128, there is another similar pipe 146^a connected with the corresponding end of the other similar cylinder.

Also connected with the valve 148 is another pipe 236 which is connected with the pipe 208. When the valve 148 connects the pipes 232 with pipes 144 and 144^a, the pipes 146 and 146^a are connected with the pipe 236. Conversely, when the valve 148 connects the pipes 232 with the pipes 146 and 146^a, the pipes 144 and 144^a are connected with the pipe 236.

Connected with the pipe 226 is a pipe 238 which leads to a pressure operated switch 240. The switch 240 is so constructed that it will operate only when the pressure applied through the pipe 238 reaches a predetermined high amount, the required high pressure being reached only after the pistons 102 have reached their limits of inward movement and after flow of oil through the pipes 226 and 106 has been stopped. When the pressure in the switch 240 rises sufficiently, the switch is closed and a circuit is established to electrically operate the valve 188 so as to establish a connection between the high pressure pipe 186 and the pipes 232, the connection with the pipe 230 being closed.

When the valve 188 has been operated to admit high pressure oil to the pipes 232, the pistons 130 are moved in one direction or the other according to the setting of the reversing valve 148. Thus the jaws are turned to twist the spider arms in the manner previously described. It will be observed that the valve 188 is not operated until after sufficient pressure has been established to move the pistons 102 which engage the jaws with the spider arms, and it will be further observed that the last said pressure cannot be established until after the several carriers or plungers 42 have been moved to their inner positions. The twisting mechanism cannot operate prematurely and can operate only after the jaws have been properly engaged with the spider arms.

A pipe 242 connected with the pipes 232 leads to a pressure switch 244 which is set to operate only upon the application thereto of a high pressure. Only when the pistons 130 reach their limits of movement, as determined by the stop 152 or 154, is the pressure in the pipes 232 and 242 increased to such an extent that the pressure switch 244 is operated. Thereupon the solenoid 196 is de-energized and the solenoid 198 is energized, the switch 170 being moved from its described forward position to its described return position. At the same time the valve 184 is operated so as to be returned to its initial position. With the switch 170 in its

5 return position and with the valve 184 operated as described, the low pressure supply pipes 164 are connected with the pipe 202 and the pipe 200 is connected with the return pipe 204.

10 With the valve 170 in the last said position low pressure oil flows through the pipes 164, 202, 208 and 36 to the cylinder 30 below the piston 32, the piston moving upward to withdraw the tool 26 from engagement with the spider. Oil from the upper portion of the cylinder 30 flows through the pipes 34, 206, 200 and 204 into the tank 156.

15 Simultaneously with the foregoing, oil flows through the pipes 202, 110, 110^a, 110^b and 110^c to the inner ends of the cylinders 104, thus moving the pistons 102 outward. As the pistons move outward, the jaws 70 and 72 are released from gripping engagement with the spider arms. By-pass pipes 246 are provided with a 20 check valve 248 included therein, these pipes connecting the pipe 106 with the pipe 220. Oil from the outer ends of the cylinders 104 flows through the pipes 106, 106^a, 106^b and 106^c, 246, 220, 200 and 204 into the tank 156.

25 Simultaneously with the foregoing, oil flows through the pipes 202, 52, 52^a, 52^b and 52^c into the inner ends of the cylinders 46, the pistons 48 being moved outward to move the plungers 42 and the jaws 70 and 72 outward from their 30 positions of engagement with the spider arms. A by-pass pipe 250 is provided having a check valve 252 therein, the said pipes 250 connecting the pipes 50, 50^a, 50^b and 50^c with the pipe 210. As the pistons 48 move outward, oil flows from 35 the outer ends of the cylinders 46 through the pipes 50, 50^a, 50^b and 50^c, 250, 210, 206, 200 and 204 into the tank 156.

Connected with the pipe 208 is a pipe 254 which leads to a normally closed pressure switch 256. The switch 256 is so adjusted as to open its circuit only when the pressure applied thereto is increased to a predetermined amount, this pressure only being reached when all of the pistons 28, 102 and 48 have reached their limits of return movement. The switch 256 is connected to control the electrically operated valve 188. When the switch 256 is opened the circuit through the valve 188 is broken. The valve 188 then moves to disconnect the pipes 232 from the pipe 186 and to connect the pipes 232 with the pipe 230. This releases the high pressure previously applied to the hydraulic twisting units. Assuming, as before, that the valve 148 is set to connect the pipes 146 and 146^a with the pipe 236, low pressure oil flows through the pipes 236, 146 and 146^a to move the pistons 130 in the direction to return the plungers 42 and the jaws 70 and 72 to their initial positions. When the pistons 130 move as last above-described, oil flows from the cylinders 128 through 60 the pipes 146, 146^a, 232 and 230 into the tank 156.

65 The provision of the pressure switch 256 and its electrical connection with the electrically operated valve 188 insures the maintenance of pressure in the cylinders 128 until all of the other pistons have been moved to fully release the spider, thus holding the pistons 130 in their spider twisted positions. Only after the spider has been fully released are the pistons 130 moved to restore the plungers 42 and the jaws 70 and 72 to their initial rotative positions. This prevents any possible untwisting of the spider arms which might occur if the pistons 130 were moved prior to the complete release 70 of the jaws 70 and 72 from the spider arms.

Electrical system

Referring particularly to Fig. 12, main leads 258, 260 and 262 are provided for the motor 158. Connected with the leads 260 and 262 are leads 264 and 266 between which extend connections 268, 270, 272, 274, 276, 278, 280 and 282 with which various control switches and devices are connected. The contacts of the various switches are shown in the separated or engaged positions which they occupy when the machine is idle.

Included in the connection 268 is a motor starter coil 284 and a normally open manually operable starter switch 286. Connected in parallel with the switch 286 is a shunt 288. Interposed in the main leads 258, 260 and 262 and in the shunt 288 are pairs of normally separated contacts 284^a, 284^b, 284^c and 284^d. The last said contacts are mechanically connected for operation by the coil 284, the contacts of all of the pairs being engaged when the coil is energized and separated when the coil is de-energized. When the starter switch 286 is closed the coil 284 is energized and contacts of the several pairs are engaged to start the motor 158 and to establish a shunt circuit which keeps the coil 284 energized after the switch 286 has been permitted to open. A manually operated normally closed stop switch 290 is provided in the connection 268, this switch when opened serving to stop the motor.

Included in the connection 270 is a forward relay coil 292 and two normally open manually operable push button switches 294 and 296. Connected in parallel with the switches 294 and 296 is a shunt 298. Interposed in the shunt 298 and in the connections 272 and 274 are pairs of normally separated contacts 292^a, 292^b and 292^c. The last said contacts are mechanically connected for operation by the relay coil 292. Also included in the connection 270 are normally engaged contacts 244^a forming a part of the pressure switch 244. When the switches 294 and 296 are manually closed the coil 292 is energized and the contacts of the last said several pairs are engaged, the contacts 292^a establishing a shunt circuit which keeps the coil 292 energized after the switches 294 and 296 are opened. A manually operated switch 300 is provided having normally engaged contacts in the connection 270. The same switch has normally separated contacts 300^a in the connection 280.

The forward solenoid 196 for the valve 170 is included in the connection 272. When the relay coil 292 is energized to cause the engagement of the contacts 292^b, the solenoid 196 is energized to move the valve 170 to its forward position.

The electrically operated valve 184 is included in the connection 274 as are also the switches 64, 64^a, 64^b and 64^c. When the relay coil 292 causes the engagement of the contacts 292^c and when the switches 64, 64^a, 64^b and 64^c are closed by the carriers or plungers as previously described, the valve 184 is operated to provide high pressure for certain of the hydraulic units as previously described.

The connection 276 is not connected directly with the lead 264 but is connected indirectly therewith through the switches 64, 64^a, 64^b and 64^c. Included in the connection 276 is a relay coil 302. Also included in the connection 276 are normally separated contacts 240^a forming a part of the pressure switch 240 and normally engaged contacts 256^a forming a part of the pressure switch 256. Connected in parallel with the

switch contacts 240^a is a shunt 304. Interposed in the shunt 304 and in the connection 278 are pairs of normally separated contacts 302^a and 302^b. When the coil 302 is energized the last said contacts are engaged, the contacts 302^a establishing a shunt circuit which keeps the coil energized with the contacts 240^a separated.

The electrically operated valve 188 is included in the connection 278. The relay coil 302 is energized only after the switches 64, 64^a, 64^b and 64^c are closed and only after the contacts 240^a of the pressure switch 240 are engaged. When the relay 302 is energized the contacts 302^b are engaged as previously stated and the valve 188 is operated. The valve 188 controls the twisting operation as previously described.

Included in the connection 280 is a return relay coil 306. Also included in the said connection and in parallel with each other are the before-mentioned normally separated switch contacts 300^a, normally separated contacts 244^b forming a part of the pressure switch 244, and normally separated contacts 306^a. Normally separated contacts 306^b are included in the connection 282. The contacts 306^a and 306^b are mechanically connected for operation by the relay coil 306. When the coil is energized the said contacts are engaged, and the contacts 306^a keep the coil energized when the contacts 300^a and 244^b are separated.

The return solenoid 198 for the valve 170 is included in the connection 282. When the contacts 306^b are engaged by the action of the relay coil 306 the solenoid 198 is energized to move the valve 198 to its return position. Preferably, normally engaged contacts 292^d are also included in the connection 280. These contacts are mechanically connected with the relay coil 292 and are separated when the coil is energized. This prevents any energization of the relay coil 306 except when the relay coil 292 is de-energized. It is thus impossible to energize the solenoid 198 while the solenoid 196 is energized.

A manually operable emergency stop switch is provided having normally engaged contacts 308^a and 308^b in the leads 204 and 206. The stop switch may be connected for operation by a suitably located foot treadle which is not shown. The opening of the stop switch will stop all action of the machine, excepting only the main motor and the pumps.

General summary of operation

Initially the several parts of the machine are in the positions shown in Figs. 1, 2, 3 and 5, and the switch 170 is in its neutral position with no hydraulic connections established through it. The operator places a spider on the central locator and then closes both push button switches 294 and 296. The provision of two switches insures the location of the operator's hands at positions such that no injury can result.

The closing of the switches 294 and 296 energizes the relay 292 and engages the contacts 292^b to energize the solenoid 196 and move the valve 170 to its forward position. At the same time the contacts 292^d are separated, thus preventing any possible energization of the relay coil 306. Thereupon, as previously described, the tool 26 is engaged with the spider to lightly clamp it and the several carriers or plungers 42 are moved inward to position the jaws 70 and 72 of the several pairs at opposite sides of the spider arms and in gripping relationship therewith. As the carriers and jaws move inward the flanges on the jaws 70, 70 engage the spider arms to slightly

turn the spider, if necessary, so as to accurately locate it in position for twisting.

When the carriers or plungers move inward, they close the series switches 64, 64^a, 64^b and 64^c. The contacts 292^c have been previously engaged by the action of the relay coil 292 and as soon as all four of the series switches have been closed the valve 184 is operated to supply high pressure as previously described. The contacts 292^c in the circuit of the valve 184 which are controlled by the relay coil 292, make it impossible for the valve to be operated except when the relay is energized to maintain the main valve 170 in its forward position. The high pressure from the valve 184 serves to press the tool 26 downward to effect the marking of the spider and to more firmly clamp it. The high pressure also presses the carriers or plungers inward to firmly hold them in their inner positions. In addition, the high pressure, acting through the pressure operated valve 224 and through the pressure reducing valve 228, serves to move the pistons 102 to cause the jaws 70 and 72 to firmly grip the respective spider arms.

As soon as the jaws have been engaged with the spider arms the pressure at the switch 240 is increased sufficiently to operate the said switch, the contacts 240^a thereof being engaged to energize the relay coil 302. The relay coil 302 when energized causes the engagement of the contacts 302^b, and the electrically operated valve 188 is operated to permit high pressure oil to flow to the hydraulic twisting units which then act to turn the carriers or plungers 42 and the jaws 70 and 72 so as to twist the spider arms as previously described.

When the twisting is completed the pressure at the switch 244 is increased sufficiently to operate the said switch, the contacts 244^a thereof being separated and the contacts 244^b thereof being engaged. The separation of the contacts 244^a de-energizes the relay coil 292 which in turn de-energizes the solenoid 196 and operates the pressure valve 188. The de-energizing of the relay coil 292 also serves to re-engage the contacts 292^d to permit the return relay coil 306 to be energized. The engagement of the contacts 244^b energizes the return relay coil 306 which in turn energizes the return solenoid 198. The solenoid 198 moves the valve 170 to its return position, and low pressure oil is then supplied as previously described to withdraw the tool 26 from the spider, to disengage the jaws 70 and 72 from the spider arms and to return the carriers or plungers and the jaws to their outermost positions. Pressure at the switch 240 is reduced so that the contacts 240^a thereof are separated but the relay coil 302 is not immediately de-energized as the said coil is connected in series with the normally engaged contacts 256^a of the pressure switch 256. When the several parts have been fully moved to their return positions the pressure at the switch 256 is increased sufficiently to operate it, and the contacts 256^a thereof are thereupon separated. This de-energizes the relay coil 302 which thereupon separates the contacts 302^b. The separation of the contacts 302^b permits the valve 188 to return to its original position, thus establishing a connection between the pipes 232 and 230. High pressure is thus released at the hydraulic twisting units, and the low pressure oil is permitted to operate the said units as previously described so as to return the twisting mechanism to its initial position.

As the result of the foregoing, the parts of the

machine are restored to their original positions and the operator can remove the twisted spider from the locator and place an untwisted spider thereon. The various operations previously described are then repeated.

The operator at any time during the cycle of operations can stop the functioning of the machine by opening the emergency stop switch having the contacts 308 and 308^a. At any time during the forward movements of the several parts of the machine, the operator can operate the switch 300 to de-energize the forward relay coil 292 and the forward solenoid 196 and energize the return relay coil 306 and the return solenoid 198. When this is done, the forward movements of the parts are stopped and the parts are moved to their return positions.

During the twisting movements of the spider arms, the metal thereof is in a condition of flow and the twisting movement is relatively slow and is continuous from the beginning thereof to the end thereof. By reason of the flow condition of the metal and the steady continuous movement thereof, there is no tendency of the spider arms to untwist after being released by the jaws.

The jaws which engage opposite spider arms are exactly opposite each other and are turned about axes which are exactly opposite and preferably exactly in alignment. This prevents any possible circumferential shifting of the spider arms during twisting.

The extent of twisting can be accurately determined by the setting of the stops 152 and 154 as previously described. The direction of twisting can be changed by manually changing the position of the reversing valve 148 and by correspondingly adjusting the stops 152 and 154.

While the machine is primarily intended for the twisting of previously untwisted spiders, it will be obvious that the machine may be used, if desired, for increasing or decreasing the twist of previously twisted spiders. When this is to be done, one of the stops 152 or 154 is so adjusted that the carriers and jaws, when in their returned positions, are at angles corresponding to the angles to which the spider arms were previously twisted. The other stop is set to determine the amount of additional twisting or untwisting which is required.

The invention claimed is:

1. In a machine for twisting fan spiders each having a central portion and a plurality of angularly spaced arms extending outward therefrom, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, mechanism for moving the carriers inward to bring the jaws of the corresponding pairs into opposed gripping relationship with the respective spider arms, mechanism for relatively moving the jaws of the said pairs when in their said gripping relationship to cause them to grip the respective spider arms, and mechanism operable with the jaws in gripping engagement for turning the said carriers and jaws in gripping engagement for turning the said carriers and jaws about horizontal axes to twist the arms of the spider relatively to the central portion thereof.

2. In a machine for twisting fan spiders each having a central portion and a plurality of angularly spaced arms extending outward therefrom, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, mechanism operable independently of the clamping means for moving the several carriers inward to bring the jaws of the corresponding pairs into opposed gripping relationship with the respective spider arms, means normally dependent upon the prior action of the clamping means for actuating the last said mechanism, mechanism for relatively moving the jaws of the said pairs when in their said gripping relationship to cause them to grip the respective spider arms, and mechanism operable with the jaws in gripping engagement for turning the said carriers and jaws about horizontal axes to twist the arms of the spider relatively to the central portion thereof.

3. In a machine for twisting fan spiders each having a central portion and a plurality of angularly spaced arms extending outward therefrom, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, mechanism for moving the several carriers inward to bring the jaws of the corresponding pairs into opposed gripping relationship with the respective spider arms, mechanism operable independently of the jaw and carrier moving mechanism for relatively moving the jaws of the said pairs when in their said gripping relationship to cause them to grip the respective spider arms, means dependent on the prior inward movement of the carriers and jaws for actuating the last said mechanism, and mechanism operable with the jaws in gripping engagement for turning the said carriers and jaws about horizontal axes to twist the arms of the spider relatively to the central portion thereof.

4. In a machine for twisting fan spiders each having a central portion and a plurality of angularly spaced arms extending outward therefrom, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, mechanism for moving the several carriers inward to bring the jaws of the corresponding pairs into opposed gripping relationship with the respective spider arms, mechanism for relatively moving the jaws of the said pairs when in their said gripping relationship to cause them to grip the respective spider arms, mechanism operable with the jaws in gripping engagement and operable independently of the jaw moving mechanism for turning the said carriers and jaws about horizontal axes to twist the arms of the spider relatively to the central portion thereof, and means normally dependent upon the prior action of the jaw moving mecha-

nism for operating the mechanism for turning the carriers and jaws.

5. In a machine for twisting fan spiders each having a central portion and a plurality of angularly spaced arms extending outward therefrom, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, mechanism operable independently of the clamping means for moving the several carriers inwardly to bring the jaws of the corresponding pairs into opposed gripping relationship with the respective spider arms, means normally dependent upon the prior action of the clamping means for actuating the last said mechanism, mechanism operable independently of the jaw and carrier moving mechanism for relatively moving the jaws of the said pairs when in their said gripping relationship to cause them to grip the respective spider arms, means dependent on the prior inward movement of the carriers and jaws for actuating the last said mechanism, and mechanism operable with the jaws in gripping engagement for turning the said carriers and jaws about horizontal axes to twist the arms of the spider relatively to the central portion thereof.

6. In a machine for twisting fan spiders each having a central portion and a plurality of angularly spaced arms extending outward therefrom, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, mechanism for moving the several carriers inward to bring the jaws of the corresponding pairs into opposed gripping relationship with the respective spider arms, mechanism operable independently of the jaw and carrier moving mechanism for relatively moving the jaws of the said pairs when in their said gripping relationship to cause them to grip the respective spider arms, means dependent on the prior inward movement of the carriers and jaws for actuating the last said mechanism, mechanism operable with the jaws in gripping engagement and operable independently of the jaw moving mechanism for turning the said carriers and jaws about horizontal axes to twist the arms of the spider relatively to the central portion thereof, and means normally dependent upon the prior action of the jaw moving mechanism for operating the mechanism for turning the carriers and jaws.

7. In a machine for twisting fan spiders each having a central portion and a plurality of angularly spaced arms extending outward therefrom, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, mechanism for moving the several carriers inward and outward, means acting successively to operate the clamping means in the forward direction so as to effect clamping

and to operate the carrier moving mechanism in the forward direction so as to bring the jaws into opposed gripping relationship with the respective spider arms and to operate the jaw moving mechanism in the forward direction so as to cause the jaws to grip the respective spider arms and to operate the carrier turning mechanism in the forward direction so as to cause the jaws to twist the spider arms, and means subsequently acting successively to operate the clamping means in the return direction to release the spider and to operate the jaw moving mechanism in the return direction so as to release the spider arms and to operate the carrier moving mechanism in the return direction so as to move the jaws out of gripping relationship with the spider arms and to operate the carrier turning mechanism in the return direction so as to restore the carriers and jaws to their initial rotative positions.

8. A machine for twisting fan spiders as set forth in claim 7, wherein means is provided which normally serves to prevent the return movement of the carrier turning mechanism until after the return movements of the clamping means and of the jaw moving mechanism and of the mechanism for moving the carriers inward and outward.

9. In a machine for twisting fan spiders each having a central portion and a plurality of angularly spaced arms extending outward therefrom, the combination of a locator for engaging the bottom of the central portion of a spider, a clamping tool above the locator, a hydraulic unit for moving the clamping tool, means for supplying oil under pressure to the hydraulic unit to cause it to move the tool downward to clamp the spider, a plurality of carriers movable horizontally inward and outward and corresponding in number and in angular spacing to the spider arms, a pair of gripping jaws individual to and mounted on the inner end portion of each carrier, a plurality of hydraulic units for moving the several carriers, means for supplying oil under pressure to the last said hydraulic units to cause them to move the several carriers inward and to thereby bring the jaws of the corresponding pairs into gripping relationship with the respective spider arms, means causing the last said oil supplying means to be dependent for its operation upon the prior application to the first said hydraulic unit of oil pressure sufficient to effect clamping, mechanism for relatively moving the jaws of the said pairs when in their said gripping relationship to cause them to grip the respective spider arms, and mechanism operable with the jaws in gripping engagement for turning the said carriers and jaws about horizontal axes to twist the arms of the spider relatively to the central portion thereof.

10. In a machine for twisting fan spiders each having a central portion and a plurality of angularly spaced arms extending outward therefrom, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, a plurality of hydraulic units for moving the several carriers, means for supplying oil under relatively low pressure to the hydraulic units to cause them to move the carriers inward and to thereby bring the jaws of the corresponding pairs into opposed gripping relationship with the respective spider arms, means dependent upon the

movement of the carriers approximately to their inner positions for applying a relatively high pressure to the oil in the hydraulic units so as to firmly hold the carriers in their said inner positions, mechanism for relatively moving the jaws of the said pairs when in their said gripping relationship to cause them to grip the respective spider arms, and mechanism operable with the jaws in gripping engagement for turning the said carriers and jaws about horizontal axes to twist the arms of the spider relatively to the central portion thereof.

11. In a machine for twisting fan spiders each having a central portion and a plurality of angularly spaced arms extending outward therefrom, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, a plurality of hydraulic units for moving the several carriers, means for supplying oil under relatively low pressure to the hydraulic units to cause them to move the carriers inward and to thereby bring the jaws of the corresponding pairs into opposed gripping relationship with the respective spider arms, a plurality of normally open electric switches connected in series, means for closing the respective switches by the several carriers upon movement thereof approximately to their inner positions, an electrically operated valve connected in series with the switches, the said valve serving upon the closing of all of the switches to apply a relatively high pressure to the oil in the hydraulic units so as to firmly hold the carriers in their inner positions, mechanism for relatively moving the jaws of the said pairs when in their said gripping relationship to cause them to grip the respective spider arms, and mechanism operable with the jaws in gripping engagement for turning the said carriers and jaws about horizontal axes to twist the arms of the spider relatively to the central portion thereof.

12. In a machine for twisting fan spiders each having a central portion and a plurality of angularly spaced arms extending outward therefrom, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, mechanism for moving the several carriers inward to bring the jaws of the corresponding pairs into opposed gripping relationship with the respective spider arms, a plurality of hydraulic units for relatively moving the jaws of the said pairs, means for supplying oil under pressure to the said hydraulic units to cause them to relatively move the jaws of the said pairs to cause them to grip the respective spider arms, means causing the said oil supplying means to be dependent for its operation upon the prior movement of the carriers and jaws to their inner positions, and mechanism operable with the jaws in gripping engagement for turning the said carriers and jaws about horizontal axes to twist the arms of the spider relatively to the central portion thereof.

13. In a machine for twisting fan spiders each having a central portion and a plurality of angularly spaced arms extending outward there-

from, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, mechanism for moving the several carriers inward to bring the jaws of the corresponding pairs into opposed gripping relationship with the respective spider arms, a plurality of hydraulic units for relatively moving the jaws of the said pairs, a plurality of normally open electric switches associated with the respective carriers and connected in series, means for closing the several switches by the respective carriers upon movement thereof approximately to their inner positions, an electrically operated valve connected in series with the switches, the said valve serving upon the closing of all of the switches to supply oil under pressure to the said hydraulic units to cause them to relatively move the jaws of the said pairs to cause them to grip the respective spider arms, and mechanism operable with the jaws in gripping engagement for turning the said carriers and jaws about horizontal axes to twist the arms of the spider relatively to the central portion thereof.

14. In a machine for twisting fan spiders each having a central portion and a plurality of angularly spaced arms extending outward therefrom, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, mechanism for moving the several carriers inward to bring the jaws of the corresponding pairs into opposed gripping relationship with the respective spider arms, mechanism for relatively moving the jaws of the said pairs when in their said gripping relationship to cause them to grip the respective spider arms, a hydraulic unit for turning the said carriers and jaws about horizontal axes to twist the arms of the spider relatively to the central portion thereof, and means normally dependent upon the prior action of the jaw moving mechanism for supplying oil under pressure to the said hydraulic unit to cause it to turn the carriers and jaws as aforesaid.

15. In a machine for twisting fan spiders each having a central portion and a plurality of angularly spaced arms extending outward therefrom, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, mechanism for moving the several carriers inward to bring the jaws of the corresponding pairs into opposed gripping relationship with the respective spider arms, a plurality of hydraulic units for relatively moving the jaws of the said pairs, means for supplying oil under pressure to the said hydraulic units to cause them to relatively move the jaws to cause them to grip the respective spider arms, a hydraulic unit for turning the said carriers and jaws about horizontal axes to twist the arms of the spider relatively to the central portion thereof, means for

6 24 supplying oil under pressure to the last said hydraulic unit, and means causing the last said oil supplying means to be dependent for its operation upon the prior application to the first said hydraulic units of oil pressure sufficient to effect gripping.

16. In a machine for twisting fan spiders each having a central portion and a plurality of angularly spaced arms extending outward therefrom, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, mechanism for moving the several carriers inward to bring the jaws of the corresponding pairs into opposed gripping relationship with the respective spider arms, a plurality of hydraulic units for relatively moving the jaws of the said pairs, means for supplying oil under pressure to the said hydraulic units to cause them to relatively move the jaws to cause them to grip the respective spider arms, means causing the said oil supplying means to be dependent for its operation upon the prior movement of the carriers and jaws to their inner positions, a hydraulic unit for turning the said carriers and jaws about horizontal axes to twist the arms of the spider relatively to the central portion thereof, means for supplying oil under pressure to the last said hydraulic unit, and means causing the last said oil supplying means to be dependent for its operation upon the prior application to the first said hydraulic units of oil pressure sufficient to effect gripping.

17. In a machine for twisting fan spiders each having a central portion and a plurality of angularly spaced arms extending outward therefrom, the combination of a locator for engaging the bottom of the central portion of a spider, a clamping tool above the locator, a hydraulic unit for moving the clamping tool, a plurality of carriers movable horizontally inward and outward and corresponding in number and in angular spacing to the spider arms, a pair of gripping jaws individual to and mounted on the inner end portion of each carrier, a plurality of hydraulic units for moving the several carriers, a plurality of hydraulic units for relatively moving the jaws of the said pairs when in their said gripping relationship to grip the respective spider arms, a hydraulic unit operable with the jaws in gripping engagement for turning the said carriers and jaws about horizontal axes, means including pipes and valves for supplying oil under pressure to all of the hydraulic units to cause them to act successively in the forward directions to move the clamping tool into engagement with the spider and to move the several carriers inward so as to bring the jaws into gripping relationship with the spider arms and to relatively move the jaws of the said pairs to cause them to grip the respective spider arms and to turn the carriers so as to cause the jaws to twist the spider arms, means including pipes and valves for supplying oil under pressure to all of the hydraulic units to cause them to act successively in the return directions to move the clamping tool out of engagement with the spider and to relatively move the jaws of the said pairs to cause them to release the respective spider arms and to move the several carriers outward so as to bring the jaws out of gripping relationship.

with the spider arms and to turn the carriers in the opposite direction to restore the carriers and jaws to their initial rotative positions, and a main valve having forward and return positions for causing the two said forward and return oil supplying means to act alternately.

18. A machine for twisting fan spiders as set forth in claim 17, wherein an electrical pressure switch is provided operable by increased pressure resulting from the completion of movement of the hydraulic unit for turning the carriers and jaws, and wherein means is provided which is controlled by the pressure switch and which serves after the operation thereof to move the main valve from its forward position to its return position.

19. A machine for twisting fan spiders as set forth in claim 17, wherein the first said oil supplying means includes an electrically operated valve, wherein an electrical pressure switch is provided operable by increased pressure resulting from the completion of movement of the hydraulic units for relatively moving the jaws, wherein means is provided which is controlled by the pressure switch and which serves to operate the last said valve to supply oil in the forward direction to the hydraulic unit for turning the carriers and jaws, wherein a second electrical pressure switch is provided operable by increased pressure resulting from the completion of movement of the hydraulic unit for turning the carriers and jaws, and wherein means is provided which is controlled by the second pressure switch and which serves after the operation thereof to move the main valve from its forward position to its return position.

20. A machine for twisting fan spiders as set forth in claim 19, wherein a third electrical pressure switch is provided operable by increased pressure resulting from the completion of the return movements of all of the hydraulic units except that for turning the carriers and jaws, and wherein means is provided which is controlled by the last said pressure switch and which serves upon the operation thereof to operate the said valve in the first said oil supplying means to release the pressure previously applied to the hydraulic unit for turning the carriers and jaws and to thereby permit the last said unit to operate in the return direction.

21. In a machine for twisting fan spiders each having a centrally apertured central portion and a plurality of angularly spaced arms extending outwardly therefrom, the combination of a spider locator having an upper face for engaging the bottom of the central portion of a spider which locator has a central stud projecting above the said upper face for entering and fitting the central spider aperture, a clamping tool above the said locator, means for moving the clamping tool downward to engage it with the said central spider portion so as to clamp the spider in its said position on the locator, a plurality of carriers corresponding in number and in angular spacing to the spider arms, a pair of gripping jaws individual to and mounted on the inner end portion of each carrier, mechanism for moving the several carriers and pairs of jaws horizontally inward to bring the jaws of the said pairs into opposed gripping relationship with the respective spider arms, means carried by at least one of the carriers for engaging the sides of the corresponding spider arm as the carrier moves inward which means serves to turn the spider on the stud and to thereby accurately locate the

spider in a predetermined angular position, mechanism operable after inward movement of the carriers and jaws for relatively moving the jaws of the said pairs when in their said gripping relationship to cause them to grip the respective spider arms, and mechanism operable with the jaws in gripping engagement for turning the said carriers and jaws about horizontal axes to twist the arms of the spider relatively to the central portion thereof.

22. A machine for twisting fan spiders as set forth in claim 21, wherein the means for engaging a spider arm and for turning the spider to accurately locate it in its said predetermined angular position is carried by a jaw of at least one of the said pairs.

23. In a machine for twisting fan spiders each having a centrally apertured central portion and a plurality of angularly spaced arms extending outwardly therefrom, the combination of a spider locator having an upper face for engaging the bottom of the central portion of a spider which locator has a central stud projecting above the said upper face for entering and fitting the central spider aperture and has means projecting above the said upper face for engaging the spider arms to at least approximately locate the spider in a predetermined angular position, a clamping tool above the said locator, means for moving the clamping tool downward to engage it with the said central spider portion so as to clamp the spider in its said position on the locator, a plurality of carriers corresponding in number and in angular spacing to the spider arms, a pair of gripping jaws individual to and mounted on the inner end portion of each carrier, mechanism for moving the several carriers and pairs of jaws horizontally inward to bring the jaws of the said pairs into opposed gripping relationship with the respective spider arms, mechanism operable after inward movement of the carriers and jaws for relatively moving the jaws of the said pairs when in their said gripping relationship to cause them to grip the respective spider arms, and mechanism operable with the jaws in gripping engagement for turning the said carriers and jaws about horizontal axes to twist the arms of the spider relatively to the central portion thereof.

24. In a machine for twisting fan spiders each having a centrally apertured central portion and a plurality of angularly spaced arms extending outwardly therefrom, the combination of a spider locator having an upper face for engaging the bottom of the central portion of a spider which locator has a central stud projecting above the said upper face for entering and fitting the central spider aperture and has means projecting above the said upper face for engaging the spider arms to approximately locate the spider in a predetermined angular position, a clamping tool above the said locator, means for moving the clamping tool downward to engage it with the said central spider portion so as to clamp the spider in its said position on the locator, a plurality of carriers corresponding in number and in angular spacing to the spider arms, a pair of gripping jaws individual to and mounted on the inner end portion of each carrier, mechanism for moving the several carriers and pairs of jaws horizontally inward to bring the jaws of the said pairs into opposed gripping relationship with the respective spider arms, means carried by at least one of the carriers for engaging the sides of the corresponding spider arm as the carrier moves inward which means serves to turn the spider on the stud and to thereby accurately locate the

the stud and to thereby accurately locate the spider in its said predetermined position, means operable after inward movement of the carriers and jaws for relatively moving the jaws of the said pairs when in their said gripping relationship to cause them to grip the respective spider arms, and mechanism operable with the jaws in gripping engagement for turning the said carriers and jaws about horizontal axes to twist the arms of the spider relatively to the central portion thereof.

25. In a machine for twisting fan spiders each having a centrally apertured central portion and a plurality of angularly spaced arms extending outward therefrom, the combination of a spider locator having an upper face for engaging the bottom of the central portion of a spider which locator has a central stud for entering and fitting the central spider aperture, a clamping tool above the said locator, means for moving the clamping tool downward to cause it to apply a relatively low pressure to the top of the central spider portion so as to lightly clamp the spider on the locator, a plurality of carriers corresponding in number and in angular spacing to the spider arms, a pair of gripping jaws individual to and mounted on the inner end portion of each carrier, mechanism for moving the several carriers and pairs of jaws horizontally inward to bring the jaws of the said pairs into opposed gripping relationship with the respective spider arms, means carried by at least one of the carriers for engaging the sides of the corresponding spider arm as the carrier moves inward which means serves to turn the spider on the stud and to thereby accurately locate the spider in a predetermined angular position, means operable after inward movement of the carriers and jaws for causing the clamping tool to apply a relatively high pressure to the spider to firmly clamp it in its said predetermined position, mechanism operable after inward movement of the carriers and jaws for relatively moving the jaws of the said pairs when in their said gripping relationship to cause them to grip the respective spider arms, and mechanism operable with the jaws in gripping engagement for turning the said carriers and jaws about horizontal axes to twist the arms of the spider relatively to the central portion thereof.

26. A machine for twisting fan spiders as set forth in claim 25, wherein the spider locator has means projecting above the upper face thereof for engaging the spider arms to at least approximately locate the spider in the said predetermined angular position prior to the engagement of the clamping tool with the spider.

27. A machine for twisting fan spiders as set forth in claim 25, wherein marking projections are provided which engage at least one face of the spider when it is lightly clamped between the locator and the clamping tool which projections are of such character that the light clamping pressure does not cause them to enter and mark the spider and are of such character that they enter and mark the spider when relatively high pressure is applied to the spider by the clamping tool.

28. A machine for twisting fan spiders as set forth in claim 25, wherein a plurality of control devices is provided for actuating the said means for causing the clamping tool to apply a relatively high pressure to the spider, the said control devices being operated by the respective carriers upon movement thereof approximately to their innermost positions and the said control devices

actuating the last said means only when all of them have been so operated.

29. In a machine for twisting fan spiders each having a centrally apertured central portion and a plurality of angularly spaced arms extending outward therefrom, the combination of a spider locator having an upper face for engaging the bottom of the central portion of a spider which locator has a central stud for entering and fitting the central spider aperture, a clamping tool above the said locator, a cylinder and piston unit for moving the clamping tool vertically, means for supplying oil under low pressure to cause the piston of the said unit to move the clamping tool downward to cause it to apply a relatively low pressure to the top of the central spider portion so as to lightly clamp the spider on the locator, a plurality of carriers corresponding in number and in angular spacing to the spider arms, a pair of gripping jaws individual to and mounted on the inner end portion of each carrier, mechanism for moving the several carriers and pairs of jaws horizontally inward to bring the jaws of the said pairs into opposed gripping relationship with the respective spider arms, means carried by at least one of the carriers for engaging the sides of the corresponding spider arm as the carrier moves inward which means serves to turn the spider on the stud and to thereby accurately locate the spider in a predetermined angular position, means operable after inward movement of the carriers and jaws for applying a relatively high pressure to the oil in the cylinder and piston unit for causing the clamping tool to apply a relatively high pressure to the spider to firmly clamp it in its said predetermined position, mechanism operable after inward movement of the carriers and jaws for relatively moving the jaws of the said pairs to cause them to grip the respective spider arms, and mechanism operable with the jaws in gripping engagement for turning the said carriers and jaws about horizontal axes to twist the arms of the spider relatively to the central portion thereof.

30. In a machine for twisting fan spiders each having a centrally apertured central portion and a plurality of angularly spaced arms extending outward therefrom, the combination of a spider locator having an upper face for engaging the bottom of the central portion of a spider which locator has a central stud for entering and fitting the central spider aperture, a clamping tool above the said locator, a cylinder and piston unit for moving the clamping tool vertically, means for supplying oil under low pressure to cause the piston of the said unit to move the clamping tool downward and to cause it to apply a relatively low pressure to the top of the central spider portion so as to lightly clamp the spider on the locator, a plurality of carriers corresponding in number and in angular spacing to the spider arms, a pair of gripping jaws individual to and mounted on the inner end portion of each carrier, mechanism for moving the several carriers and pairs of jaws horizontally inward to bring the jaws of the said pairs into opposed gripping relationship with the respective spider arms, means carried by at least one of the carriers for engaging the sides of the corresponding spider arm as the carrier moves inward which means serves to turn the spider on the stud and to thereby accurately locate the spider in a predetermined angular position, a plurality of control devices operated by the respective carriers upon movement thereof ap-

proximately to their innermost positions, means actuated by the control devices when all of them have been operated and thereupon serving to apply a relatively high pressure to the oil in the cylinder and piston unit for causing the clamping tool to apply a relatively high pressure to the spider so as to firmly clamp it in its said predetermined position, mechanism operable after inward movement of the carriers and jaws for relatively moving the jaws of the said pairs to cause them to grip the respective spider arms, and mechanism operable with the jaws in gripping engagement for turning the said carriers and jaws about horizontal axes to twist the arms of the spider relatively to the central portion thereof.

31. In a machine for twisting fan spiders each having a central portion and a plurality of angularly spaced arms extending outward therefrom, the combination of means for clamping the central portion of a spider to hold it in a fixed horizontal position, a plurality of carriers corresponding in number and in angular spacing to the spider arms, a plurality of gripping jaws mounted on the inner end portions of the respective carriers and in fixed relation thereto, a second plurality of jaws mounted on the inner end portions of the respective carriers and located respectively in opposed relationship to the first said jaws, the second said jaws being pivoted to the respective carriers for movement about transverse horizontal axes, mechanism for moving the several carriers and the corresponding jaws horizontally inward to bring the jaws into opposed gripping relationship with the respective spider arms, mechanism operable when the jaws are in their said gripping relationship for moving the second said jaws about their pivotal axes to grip the respective spider arms, and mechanism operable with the jaws in gripping engagement for turning the said carriers and jaws about horizontal axes to twist the arms of the spider relatively to the central portion thereof.

32. In a machine for twisting fan spiders each having a central portion and a plurality of angularly spaced arms extending outward therefrom, the combination of means for clamping the central portion of a spider to hold it in a fixed horizontal position, a plurality of carriers corresponding in number and in angular spacing to the spider arms, a plurality of gripping jaws at the inner end portions of the respective carriers and in fixed relation thereto, a second plurality of jaws at the inner end portions of the respective carriers and located respectively in opposed relationship to the first said jaws, the second said jaws being pivoted to the respective carriers for movement about transverse horizontal axes, mechanism for moving the several carriers and the corresponding jaws horizontally inward to bring the jaws into opposed gripping relationship with the respective spider arms, hydraulic units associated with the respective carriers for moving the second said jaws about their pivotal axes to grip the respective spider arms, means for supplying oil under pressure to the said units to cause them to move the jaws as aforesaid when the carriers have been moved inward to bring the jaws into the said relationship with the spider arms, and mechanism operable with the jaws in gripping engagement for turning the said carriers and jaws about horizontal axes to twist the arms of the spider relatively to the central portion thereof.

33. In a machine for twisting fan spiders each having a central portion and a plurality of angularly spaced arms extending outward therefrom, the combination of means for clamping the central portion of a spider to hold it in a fixed horizontal position, a plurality of carriers corresponding in number and in angular spacing to the spider arms, a plurality of gripping jaws at the inner end portions of the respective carriers and in fixed relation thereto, a second plurality of jaws at the inner end portions of the respective carriers and located respectively in opposed relationship to the first said jaws, the second said jaws being pivoted to the respective carriers for movement about transverse horizontal axes, mechanism for moving the several carriers and the corresponding jaws horizontally inward to bring the jaws into opposed gripping relationship with the respective spider arms, mechanisms associated with the respective carriers and each comprising a cylinder and piston unit and an inwardly movable plunger having a cam face for moving the corresponding pivoted jaw into gripping engagement with the corresponding spider arm, means for supplying oil under pressure to the said units to cause them to move the jaws as aforesaid when the carriers have been moved inward to bring the jaws into the said relationship with the spider arms, and mechanism operable with the jaws in gripping engagement for turning the said carriers and jaws about horizontal axes to twist the arms of the spider relatively to the central portion thereof.

34. In a machine for twisting fan spiders each having a central portion and a plurality of angularly spaced arms extending outward therefrom, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, mechanism for moving the several carriers inward to bring the jaws of the corresponding pairs into opposed gripping relationship with the respective spider arms, mechanism for relatively moving the jaws of the said pairs when in their said gripping relationship to cause them to grip the respective spider arms, mechanism operable with the jaws in gripping engagement for turning the said carriers and jaws about horizontal axes to twist the arms of the spider relatively to the central portion thereof, and adjustable means for limiting the extent of movement of the last said mechanism to vary the angles of twisting of the spider arms.

35. In a machine for twisting fan spiders each having a central portion and a plurality of angularly spaced arms extending outward therefrom, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, mechanism for moving the several carriers inward to bring the jaws of the corresponding pairs into opposed gripping relationship with the respective spider arms, mechanism for relatively moving the jaws of the said pairs when in their said gripping relationship to cause them to

grip the respective spider arms, mechanism operable with the jaws in gripping engagement for turning the said carriers and jaws about horizontal axes to twist the arms of the spider relatively to the central portion thereof, and means optionally serving to move the last said mechanism in either of two directions for turning the said carriers and jaws in either of two directions.

36. In a machine for twisting fan spiders each having a central portion and a plurality of angularly spaced arms extending outward therefrom, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, mechanism for moving the several carriers inward to bring the jaws of the corresponding pairs into opposed gripping relationship with the respective spider arms, mechanism for relatively moving the jaws of the said pairs when in their said gripping relationship to cause them to grip the respective spider arms, an annular member movable about a central vertical axis, connections between the annular member and the respective carriers for turning the said carriers and jaws about horizontal axes, and mechanism for moving the annular member about its said axis when the jaws are in gripping engagement with the spider arms so as to turn the carriers and jaws and thereby twist the arms of the spider relatively to the central portion thereof.

37. A machine for twisting fan spiders as set forth in claim 36, wherein adjustable means is provided for limiting the extent of movement of the annular member and for thus varying the angles of twisting of the spider arms.

38. A machine for twisting fan spiders as set forth in claim 36, wherein means is provided for causing the mechanism for moving the annular member to operate in either of two directions so as to turn the carriers and jaws in either of two directions.

39. In a machine for twisting fan spiders each having a central portion and a plurality of angularly spaced arms extending outward therefrom, the combination of means for clamping the central portion of a spider to hold it in a fixed horizontal position, a plurality of cylindrical carriers corresponding in number and in angular spacing to the spider arms, the said carriers being provided with longitudinal gear teeth, a plurality of bearings in which the respective carriers are movable inward and outward and also rotatively, a pair of gripping jaws individual to and mounted on the inner end portion of each carrier,

mechanism for moving the several carriers inward in the bearings to bring the said jaws of the corresponding pairs into opposed gripping relationship with the respective spider arms,

5 mechanism for relatively moving the jaws of the said pairs when in their said gripping relationship to cause them to grip the respective spider arms, an annular member movable about a central vertical axis, gear teeth on the annular member meshing with the gear teeth on the several carriers and serving to turn the said carriers and jaws about horizontal axes, and mechanism for moving the annular member about its said axis when the jaws are in gripping engagement with the spider arms so as to turn the carriers and jaws and thereby twist the arms of the spider relatively to the central portion thereof.

40. In a machine for twisting fan spiders each having a central portion and a plurality of angularly spaced arms extending outward therefrom, the combination of means for clamping the central portion of a spider to hold it in a fixed horizontal position, a plurality of carriers movable horizontally inward and outward and corresponding in number and in angular spacing to the spider arms, a pair of gripping jaws individual to and mounted on the inner end portion of each carrier, mechanism for moving the several carriers inward to bring the jaws of the corresponding pairs into opposed gripping relationship with the respective spider arms, mechanism for relatively moving the jaws of the said pairs when in their said gripping relationship to cause them to grip the respective spider arms, an annular member movable about a central vertical axis, connections between the annular member and the respective carriers for turning the said carriers and jaws about horizontal axes, a hydraulic unit for moving the annular member about its said axis when the jaws are in gripping engagement with the spider arms so as to turn the carriers and jaws and thereby twist the arms of the spider relatively to the central portion thereof, and a manually operable reversing valve for the hydraulic unit serving optionally to cause the said unit to move the annular member in either direction.

PETER M. SAMPATACOS.
